Attest.

E. B. MARSHALL, OF ATLANTA, GEORGIA.

Letters Patent No. 83,190, dated October 20, 1868.

IMPROVEMENT IN STATION-INDICATORS.

The Schedule referred to in these Letters Patent and making part of the same.

To all whom it may concern:

Be it known that I, E. B. MARSHALL, of Atlanta, in the county of Fulton, and in the State of Georgia, have invented certain new and useful Improvements in Combined Clock and Station-Indicator for railroad-cars; and do hereby declare that the following is a full, clear, and exact description thereof, reference being had to the accompanying drawings, and to the letters of reference marked thereon.

In the annexed drawings, forming part of this specification—

Figure 1 represents a plan view of a clock with the station-indicator attached, and

Figure 2 is a side view of the latter.

The nature of my invention consists in a movable rim, placed around a clock, with the names of each station opposite the hour the train is due; also the time the train remains at each station, fixed upon the rim, with any other information the travelling-public is in need of.

To enable others skilled in the art to make and use my invention, I will proceed to describe its construction and operation.

Place the name of the station on the movable rim A, at the time the train leaves, and the name of the last station at the time it is due there. The intermediate stations will be indicated by the time which the train

should arrive at each, by having the names of the stations put in on the movable rim.

This rim A can be moved backward and forward to suit any schedule, and secured by the aid of a spring, B, so that, should the train lose any time, it can be changed very readily by the conductor; and when a train arrives at its destination, the rim can be reversed and placed according to the time of departure, and show all the intermediate stations, and the time of arrival at each, all the way back.

The names of the stations on each road are fixed upon this rim, according to the schedule they run.

Having thus fully described my invention,

What I claim as new, and desire to secure by Letters Patent, is—

The movable and reversible rim A, when so arranged, with the names of the different stations inscribed upon it, and in combination with a clock, that said clock will show at a glance when the train or conveyance is due at any or all stations on the road, substantially as and for the purposes herein set forth.

In testimony that I claim the foregoing, I have hereunto set my hand, this 15th day of April, 1868.

E. B. MARSHALL.
